UNITED STATES PATENT OFFICE.

SMITH A. HOGE, OF RICES LANDING, PENNSYLVANIA.

MEANS FOR GENERATING STEAM.

1,118,202.

Specification of Letters Patent.

Patented Nov. 24, 1914.

Application filed January 21, 1914. Serial No. 818,432.

To all whom it may concern:

Be it known that I, SMITH A. HOGE, a citizen of the United States, residing at Rices Landing, in the county of Green and State of Pennsylvania, have invented certain new and useful Improvements in Means for Generating Steam, of which the following is a specification.

My invention relates to means for generating steam for power utilization, and has for its particular object to employ the usually waste heat of coke ovens, and also the resulting gases of combustion, containing the ordinary by-products, for economical development of the heat in the production of steam.

The invention is designed to be used in conjunction with a bank of coke ovens of any suitable type, but preferably of the tunnel oven character, and in connection with a furnace and boiler installation located in convenient relation or juxtaposition thereto, for using the waste gases under the boiler, and the partly or entirely generated steam obtained from the heat within the oven walls and surrounding the outgoing gases in their travel toward the boiler furnace.

The invention utilizes a portion of the construction illustrated and described in my prior application for patent on coke ovens, filed Oct. 23, 1913, Serial No. 796766.

One preferred arrangement of the invention, as utilized in connection with the particular form of oven shown in that application, is illustrated in the accompanying drawings, in which—

Figure 1 is a partial elevation, partly in section, showing a series of coke ovens having fuel and steam connection with the furnace and boiler of an ordinary steam boiler installation. Fig. 2 is an enlarged transverse sectional view, indicated by the line II. II. of Fig. 1. Fig. 3 is a further enlarged sectional view, transversely of one of the oven structures, showing the detail construction of the gas and steam conveying mechanism. Fig. 4 is a partial plan view of the piping connections.

In the drawings, 2 represents an ordinary steam boiler, which may be of the flue or water tube type, mounted above the furnace or combustion chamber 3 within a suitable setting 4, provided with a draft stack 5, a steam drum 6, and the usual accompany-

ing features of construction incident to steam generation, as will be well understood.

The coke oven, or series of ovens, which are ordinarily built together, are provided with the interior cavities 7 within surrounding, usually brick, walls 8, the ovens being built in series or banks providing a continuous flat upper surface for the passage of the larry or charging car for discharging the coal into the oven chambers through trunnel openings 9, 9. These trunnel openings are preferably located, in the construction herein illustrated, at each side of the middle longitudinal portion of the oven, and of the central gas outlet opening, which is ordinarily the trunnel opening, communicating directly with the atmosphere.

The arrangement shown is preferable, while easily allowing for charging of the ovens, the coal ordinarily being leveled through the end openings by suitable well-known means. It will be understood, however, that the invention is not limited to this particular arrangement of openings or of gas and steam connections, and that these may be made and arranged to suit the construction to which the invention is applied. The walls of the oven, as thus arranged, and between the adjacent chambers 2, are of considerable thickness and intended for the purpose of absorbing and retaining a very considerable and high degree of heat, due to the combustion of the bituminous matter of the coal in the coke-making operation, such heat being retained for a very considerable period of time, and being ordinarily sufficient to effect firing of the new charge of green coal, long after the coke is removed. For the purpose of utilizing this latent heat, I provide series of circulating pipes 10 which are located as closely adjacent to each other as convenient, extending longitudinally through the walls of the oven, surrounding the chamber 2 and conforming generally to the outline of the interior wall surfaces thereof.

The terminals of pipes 10, at one or both ends of the oven chamber, are connected by suitable fittings and nipples constituting header pipe connections 11, said header pipes being connected with a water supply pipe 12, one of such pipes being preferably used at each end portion of the ovens, extending longitudinally therethrough, or otherwise, as preferred.

At their upper portions the several header connections 11 are brought into circulating connection with a common supply pipe 13 by means of pipe connections 14. Such connections, as well as the connections with the water supply pipe 12 are provided with suitable controlling valves, wherever desired, and not necessarily herein specifically described or illustrated, for the purpose of cutting out any particular one or more ovens of the system. The supply pipe 13, either at one or both sides of the ovens, is designed to be connected with the steam chamber of the boiler 2, preferably through a suitable pump 15, and also preferably in connection with the additional steam supplying pipe utilizing the heat of the outgoing gases from the oven. For such purpose, pipes or conduits 16 lead upwardly from the central gas outlet openings 17 of each oven, as shown in Figs. 2 and 3, pipe 16 connecting with the common bustle pipe 18. Said pipe, by means of any suitable header connection 19, communicates with the steam supply pipe or pipes 13, whereby to collect all of the resulting steam, vapor, etc., at a common point, and facilitate connection with the pump 15. From said pump, by a connection 20, the steam and vapor is forced into the steam cavity of boiler 2, as clearly shown in Fig. 1.

For the purpose of maintaining a water supply around the outside of gas outlet connection 16, I provide a series of inclosing shells 21 providing an intervening space 22, such pipes 21 making connection with a pipe 23 surrounding bustle pipe 18, and providing the intervening steam or vapor containing space 24, having connection with pump 15 and pipe 13 by means of the header 19.

For the purpose of supplying water to the base of each connection 21, a water supply pipe 25 is provided, having nipple connections 26 therewith, by which the supply of water is constantly maintained around the outside of the base portion of gas conduits 16, the shell 21 having suitable packed connections 27 at the bottom, whereby to maintain a tight closure, and facilitate the supply of steam or vapor producing water at all times. It will be understood that the mounting of the various pipes within the oven structure, the number, the connections with the steam circulating system, the water supply, the preliminary heating thereof, the particular mechanism for providing for the utilization of the waste heat, the connections with the boiler structure, the pump mechanism, etc., are matters of detail construction within the province of the designing engineer or builder, and may be changed or varied from the constructions illustrated

and described, without departure from the invention, as specified in the following claims.

What I claim is:

1. The combination with a boiler and its furnace, of a coke oven having a vertical conduit for the waste gases leading upwardly from the oven for a short distance and connected with the furnace chamber, and a steam or vapor-containing shell surrounding said conduit and connected with the boiler and provided with a water-containing portion surrounding the vertical conduit, substantially as set forth.

2. The combination with a boiler and its furnace, of a coke oven having a vertical conduit for the waste gases leading upwardly from the oven for a short distance and connected with the furnace chamber, a steam or vapor-containing shell surrounding said conduit and connected with the boiler and provided with a water containing portion surrounding the vertical conduit, and a pump for forcing the vapor contained in said shell to the boiler, substantially as set forth.

3. The combination with a boiler and its furnace chamber, of a coke oven, a gas outlet conduit leading therefrom communicating with the furnace chamber and provided with a vertical portion leading upwardly from the oven, means surrounding said outlet conduit adapted to contain and convey water vapor and provided with a downwardly extending reservoir portion surrounding said vertical portion, series of circulation pipes embedded within the oven walls connected with said vapor conveying means, and means connecting said vapor conveying means with the boiler, substantially as set forth.

4. The combination with a boiler and its furnace chamber, of a coke oven, a gas outlet conduit leading therefrom communicating with the furnace chamber and provided with a vertical portion leading upwardly from the oven, means surrounding said outlet conduit adapted to contain and convey water vapor and provided with a downwardly extending reservoir portion surrounding said vertical portion, series of circulation pipes embedded within the oven walls connected with said vapor conveying means, and means embodying a pump connecting said vapor conveying means with the boiler, substantially as set forth.

In testimony whereof I hereunto affix my signature in the presence of two witnesses.

SMITH A. HOGE.
